UNITED STATES PATENT OFFICE

SYDNEY FREDERICK CORBY AND JAMES WASP, OF EAST MOLESEY, ENGLAND,
ASSIGNORS TO SAID CORBY

PARTITION WALL

Application filed December 9, 1927, Serial No. 238,875, and in Great Britain December 20, 1926.

This invention relates to partition walls, primarily W. C. partitions, and has for its objects economy and simplicity of erection, good appearance, capability of withstanding hard wear, and a sanitary construction.

5 According to this invention, the partition is cast or moulded in one piece, prior to erection, of suitable composition such as concrete, artificial marble, artificial stone, wood composition, or the like. The one-piece partition is provided with means such as integral portions or separate standards for securing it in a recess in the back wall and in a recess in the floor, and also with lateral projections 10 in front to constitute jambs for the doors of adjacent closets. Preferably the rear end of the partition is formed with an enlarged key or rib adapted to lie within a vertical chase in the back wall, whilst the front of the 15 partition has an enlarged foot or pedestal to be sunk within a corresponding hole in the floor. All angles of the partition are rounded and at the fixings in the wall and floor the rounded angles are arranged so that 20 they lie flush with the finished wall surface and floor level respectively.

Except for the front pedestal, the partition and extremities of the jambs are located a certain distance above ground level. Holes, 25 as required, are drilled out or otherwise formed for the fixing of door fixtures, toilet accessories and so forth.

In the case of end partitions, right or left hand single return jambs are formed.

30 Intermediate partitions have two jambs. Reinforcement may be used in the castings, particularly in the vicinity of the jambs.

The finished surface of a partition unit 35 is jointless and highly polished and may, if desired, be coloured or incorporate coloured designs.

In a modification the partition wall is formed of sections adapted to be interlocked to form a one piece structure. With such 45 an arrangement the partition structure can more conveniently be transported.

Preferably distance means are located between the front portions of adjacent partition walls and serve to maintain the walls at 50 the correct distance apart.

The partitions can be rapidly erected when the wall chases and floor sinkings are provided. Their erection can be left until the plumbing and sanitary fittings have been fixed so as to give the plumbing staff ample 55 space for their work.

The invention is illustrated in the accompanying drawings, in which Figure 1 is a side elevation. Figure 2 a front elevation thereof. Figure 3 a section on the line 3—3, Figure 4—1. Figure 4 is a section on the line 4—4, and Figure 5 a section on the line 5—5, Figure 60 2. Figure 6 is a front elevation, and Figure 7 a plan of a door jamb for an end closet. Figure 8 is a front elevation. Figure 9 a section on the line 9—9, Figure 8; and Figure 10 a section on the line 10—10, Figure 8, of distance means. Figure 11 is a side elevation, and Figure 12 a plan of a modification.

Referring more particularly to Figures 1 to 10, 1 is a partition wall which is cast or formed in one piece with an enlarged key or rib 2 which enters a chase or recess 3 formed in the back wall 4 of a row of closets. The partition wall 1 is cast or formed at its front 75 end with an enlarged foot 5 which enters a recess formed in the floor, and with flanges 6 which, together with a projecting portion 7, form double return door jambs, metal insets 8 being provided for positioning the doors. The junction of the partition wall 1 with the key or rib 2 and the foot 5, are so rounded that, when the wall is erected, the said junctions and feet form a rounded surface tangential to the plaster or other surfacing on the back 85 wall and to the floor surface. Holes, as required, are drilled or otherwise formed for the fixing of door fixtures, toilet accessories and so forth. 9 is a beading which is grooved to pass over the upper ends of the flanges 6 and 90 located in that part of the groove which is between adjacent partition walls is a distance piece 10 which abuts against the opposite flanges of the partition walls and serves thereby to maintain the walls at the required 95 distance apart.

In Figures 6 and 7 is illustrated a single return door jamb, for use in end closets, formed with an enlarged key or rib 12 which enters a chase or recess formed in the end wall, 100

In cases where the end wall is not used as an end partition for a series of compartments, a partition as hereinbefore described may be employed with a single jamb in lieu of two jambs.

5 In the modification illustrated in Figures 11 and 12, the partition wall 1 comprises a partition formed with longitudinal grooves which receive longitudinal beads or projections 13, 14, formed respectively on front and rear posts 15, 16, integral with which are pedestals 17, 18, which support the partition and which are provided with dowel pins 19, 20, entering holes formed in the partition. 10 The rear post 16 is integral with the enlarged key or rib 2, and the front post is formed with the foot 5 and with the flanges 6 and projecting portion 7. The partition and the posts are clamped together by means of a rod 21 which lies in a recess formed in the upper end of the partition, one end of the rod being secured to the rear post 16 and the other end passing through the front post 15 and receiving or being concealed by a suitably ornamented nut 22; after the posts and the partition have been secured to form a single unit the groove in which the rod 21 is located is filled in with material such as cement. With this arrangement partition structures can more readily be transported than with the arrangement illustrated in Figures 1 to 5, while the partition wall can quickly be assembled prior to erection to form a single unit.

15 35 What we claim is:—

1. In a unit partition wall, the combination of a partition, a front standard, a supporting foot on said standard adapted to enter a recess in a floor, a shoulder on said standard adapted to support the front of said partition, a rear standard, a key on said rear standard adapted to enter a keyway in a wall, a shoulder on said standard supporting the rear of said partition, interlocking keys and keyways on said standards and said partition, and means to fasten said standards to said partition.

2. In a unit partition wall, the combination of a moulded partition, a moulded front standard, means on said front standard supporting the front of said partition, means on said standard adapted to enter a recess in a floor, door-positioning means on said standard, a moulded rear standard, means on said rear standard supporting the rear of said partition, means on said rear standard adapted to enter a recess in a wall, and means interlocking said front and rear standards with said partition.

3. In a unit partition wall, the combination of a partition, a front standard, a supporting foot on said standard adapted to enter a recess in a floor, a shoulder on said standard supporting the front of said partition, door positioning means on said standard, a rear

standard, a key on said rear standard adapted to enter a keyway in a wall, a shoulder on said standard supporting the rear of said partition, upstanding interlocking keys and keyways on said standards and said partition, and clamping means above said keys and keyways adapted to clamp said standards to said partition.

70 75 In testimony that we claim the foregoing as our invention, we have signed our names this 28th day of November, 1927.

80 SYDNEY FREDERICK CORBY.
JAMES WASP.
